UNITED STATES PATENT OFFICE

2,136,720

TELEPHONIC APPARATUS

Joseph C. White, Boston, Mass.; Alice G. White,
Boston, Mass., executrix of said Joseph C.
White, deceased

Application March 20, 1936, Serial No. 69,769

2 Claims. (Cl. 179—107)

The main purposes of my invention are:

1. To produce a very powerful yet very small motor element for a hearing-aid earpiece or a mechanical amplifier unit.
2. To produce in a single earpiece unit both air conduction and bone conduction characteristics. Air conduction results from the air column being moved by the piston driven diaphragm or vibrator, while bone conduction follows from a mounting of suitable parts of the motor element with a certain degree of looseness as regards the remaining motor parts and the outside or enclosing case. By this arrangement a high degree of vibratory movement is imparted to the entire earpiece unit when the current changes in the armature coil produce corresponding flux changes in the piston-armature, causing the latter to vibrate in the permanent magnetic field, as described.
- 20 This vibrating case movement, acting on all ear surfaces in contact with the case, is transmitted by these surfaces to closely underlying mastoid bone areas and thence to the auditory centers in the brain.
- 25 This combination of air conduction and bone conduction meets the objection that by using a bone conduction device alone the eardrum, bone-chain, etc., are not given necessary exercise and the defectiveness of hearing thereby naturally increases.

Other objects will be pointed out below.

In the drawings

Figure 1 is a top plan of a device embodying my invention;

Figure 2 is a bottom plan of the same, with the bottom member removed;

Figure 3 is a section on line 3—3 of Figure 1;

Figure 4 is a detail of one of the segmental members described below;

Figure 5 is a partial side elevation of the casing of Figure 3;

Figure 6 is a detail of the pole pieces described below;

Figure 7 is a partial section, similar to that of Figure 3, but showing a microphonic attachment; and

Figures 8 and 9 are wiring diagrams described below, the ear plug occupying a different rotary position from that it occupies in Figure 1.

50 Metal casing 1 has a bottom opening 2 of the form shown in Figure 2. Bottom cover plate 3 is held to flanges 4 of the casing 1 by screws 5, casing 1 having an opening 6 for the wires described below, the wires being clamped between the top of said opening 6 and said plate 3.

Ring or cap member 7 is threaded to the outside of annular flange 8 of casing 1. Ring member 7 and the top of flange 8 clamp between them the fibre washer 10, the metal disc 11, the fibre washer 12 and the metal ring 13.

5 The metal disc or cover plate 9 is rotatable on stud 11^a, the latter being riveted to plate 11, plate 11 being perforated at 11^b, as indicated in Figure 3, to provide orifices for the passage of sound waves to the brass sound channel 9^b of 10 plate 9, said channel having a slit 9^c to permit springing of said channel.

Metal ring 14 cooperates with metal ring 13 to frictionally hold in place the depending annular flange 15 of stretch diaphragm 16, which is 15 preferably very thin, said flange being formed by forcing the ring 14 upwardly into ring 13 so as to bend the flange 15 at substantially a right angle, thus stretching the diaphragm to a desired tension and thus increasing its sensitivity. 20 The flange 15 is clamped between ring 13 and ring 14, it being understood that this formation of flange 15 is done before the several parts above mentioned are clamped between member 7 and the top of flange 8.

25 To the diaphragm 16 is soldered, or otherwise secured, the head 17^a of a cylindrical piston-armature 17 of iron or other suitable magnetic material.

The head 17^a is sufficiently larger, transversely, 30 than the opening in pole piece 18 to provide the proper path for the flux of the permanent ring magnet 19 which is held in place by screw 20 (Figures 8 and 9) which passes through pole piece 21 and engages the threaded hole 22 of 35 segmental brass washer 23.

Coil 24 is within the magnet 19 and is held in place by pole pieces 18 and 21. Screw 25 is mounted on pole piece 21 to adjust the lower air gap between the screw 25 and the cylindrical 40 armature 17. Pole piece 18 is held in place by screw 18^a and pole piece 21 is held in place by screw 20.

The ear plug 26 is preferably of rubber or other non-metallic material and, in the form 45 shown, frictionally engages the spring channel 9^b. The ear plug may be readily removed for cleansing and for subsequent replacement. The ear plug 26 is formed with a head 27 consisting of a plurality of protuberances 28 with ventilating grooves 29 between adjacent protuberances. 50

Stud 11^a is riveted to plate 11 at 11^c, the stud having a portion 11^d which is deeper than the thickness of plate 9 so that plate 9 may turn, with only spring friction, on plate 11. Stud 11^a has 55

also a reduced portion 11^e , the lower end of which is riveted to the bottom of plate 11 , without cramping the rotative movement of plate 9 .

Stud 11^a is grooved at 11^f to receive the spring 5 loop portion 30 of ear wire 31 , the latter being tipped, as shown, from about point 32 to the free end 33 with fairly soft rubber or its equivalent, the rubber being applied by dipping the wire in straight condition into the rubber. Preferably I 10 dip the wire, as from 32 to 33 , by hand into the rubber compound and then hang the wire by the loop portion. The rubber which has run down becomes of substantially the form shown, that is, tapering toward end 33 and forming a globular 15 covering for the free end of the wire. If desired, in order to increase the rubber coating and tip, I may dip several times, so that the covered wire will fit the ear of the particular user, the repeated dipping resulting in a proportionately increased 20 globular end portion relative to the remainder of the covering portion, the globular end, by my method, building up faster than the rest of the covering material. The rubber covered portion preferably engages the concha of the ear thereby 25 holding the device very firmly in place without abrasion or irritation or any harmful effect.

In Figure 7, which represents an amplifier unit, the diaphragm and the parts below it and casing 1 are the same as the corresponding parts in 30 Figure 3. An annular head 34 of insulating material is held to case 1 by internally-threaded clamp ring 35 . If the diaphragm 16 is not stretched, as shown, the upper surface in contact with carbon particles 35^a is properly surfaced, as by gold 35 plating or being carbonized. The carbon particles are held in place within head 34 and beneath carbon plate 36 , the latter being held by spring cap 37 which contacts carbon plate 36 at 38 . In Figure 7 I have shown a diaphragm but any suitable 40 vibrator may be used.

In Figure 8 the current flows in the primary circuit from battery 50 through wire 51 , microphone diaphragm 52 with its other microphonic elements 53 , wire 54 , primary coil 55 , wires 56 , 57 , 58 , 59 to the variable resistance 60 and back to 45 the battery. The changing current in the primary circuit induces an alternating current in the secondary circuit which current flows from secondary coil 61 through wire 62 , 63 , 64 and around the coil in the direction indicated by the arrows (in full lines) and then back through wires 65 , 66 and 67 to the secondary coil 61 . Wires 63 and 66 are suitably held as by screws 63^a and 66^a suitably insulated by piece 63^b . If 50 the pole piece 18 is a permanent north pole then the pole piece 21 will be a south pole and when the current flows as above described the head 17^a of the piston will be a north pole and thus repelled from pole piece 18 and the similar action of 55 repulsion occurs at the lower end of piston armature 17 with the result that the latter is raised. With the reversal of current in coil 61 and a flow as indicated by the broken arrows an opposite result occurs, that is, the polarity of the ends of the piston armature is changed and the piston is attracted or pulled down.

In Figure 9 the current flows in the primary circuit from battery 50 through wires 68 and 69 , wire 68 leading to microphone elements 70 . 70 Thence current flows through wire 71 to the primary 72 of a transformer and thence by wire 72^a to the variable resistance switch 73 and wire 74 back to battery 50 . Branching from wire 68 is wire 69 leading to primary 75 of a second transformer, and thence by wire 76 to microphone ele-

ments 77 and thence through the diaphragm 16 (not shown in Figure 9) by proper grounding to the case 1^a and so to wire 78 to variable resistance switch 73 and wire 74 to the battery 50 . The current generated in the secondary 79 of the transformer, whose primary is 72 , is carried by wire 80 to piston coil 24 of the amplifier, thence by wire 81 to the secondary 79 .

From the secondary 82 of the transformer, whose primary is 75 , leads wire 66 which goes to coil 24 beneath cap 8 , and thence by wire 63 back to secondary 82 .

In Figure 9 the full line arrows indicate current flowing in one direction and the dotted line arrows indicate current flowing in the opposite direction. 15 The action of attraction and repulsion on the piston in the amplifier and on the piston in the ear piece is the same as described in connection with Figure 8.

By means of the rotatable front plate of the 20 earpiece the unit can be adapted to either ear simply by moving the sound tube either forward or backward in relation to the cord which depends normally vertically. The earwire is snapped on in either a right or left position so as 25 to engage the proper groove of either ear lobe.

Furthermore, by means of the combination of rotatable front plate, sound-orifice plate and the offset sound-tube the entire unit is allowed to enter bodily into the earlobe and thus brings the 30 back of the case practically flush with the earlobe.

A further advantage of the front-plate construction is that the sound emitted by the diaphragm is not throttled by passage through a relatively small hole in the earpiece cap center and then through a more or less devious passage to the ear canal. By my structure the air above the diaphragm is, during diaphragm activity, given a pressure head and is forced, with increased velocity, directly through the sound tube into the meatus to impinge with increased force against the eardrum.

Another advantage of the front-plate, sound-tube and earwire structure is that the ear is ventilated, the body heat within the ear escapes, the wearer feels a constant sense of comfort and there is no danger of fungus growth and inflammation due to trapping of the internal heat as is common when moulded shapes, especially rubber, are used.

Long experiment has proved that the arrangement of sound tube and plate allows proper ventilation without a tendency to "howl", to overcome which individually moulded, closefitting rubber and other plugs are resorted to.

A signal advantage of my motor construction is that by the use of diaphragms or vibrators of different thicknesses in combination with variations in piston-armature sizes or weights accentuation of desired tone-ranges can be brought about to suit the hearing requirements of individual users.

While it is theoretically desirable to have a light vibrating member in the amplifying and earpiece units of hearing aids, it has been found by experiments with my structure herein described that, either with the push-pull effect of transformers in either or both of the circuits, as well as without transformers, a person with a degree of deafness of 95 percent was able to repeat sentences and phrases whispered at a distance of fifty feet.

Another advantage of my principle in an auricular telephone is the noticeably high degree of the definition characteristic in both speech and 75

music with remarkably large volume on a low current consumption. This makes possible the use of a much smaller battery instead of the usual 3-cell 4.5 volt heavy battery which the user finds so uncomfortable to carry.

Another noteworthy advantage of my novel principle as applied to earphones is that it allows the use of a powerful and efficient earpiece small enough to enter a child's ear, and 10 an exceedingly powerful amplifier unit that can be housed in a case no larger than that of the earpiece.

In using my principle it is found that, once the piston head air-gap (top air-gap) is fixed 15 at the most desirable predetermined length, a very delicate adjustment can be made at any time by a slight movement of the lower air-gap adjusting screw which has a very fine thread.

A further desirable feature of my invention is 20 the manner in which it lends itself to rugged construction and consequent durability. For more than eighteen months an experimental set was used by me in trials in cases of deafness. On two occasions the transmitter and amplifier case was pulled accidentally from a table top to the floor, each time by a different user. After each fall the set continued working without adjustment and no subsequent adjustment was found necessary.

My invention comprises a vibratory device in which an element, such as a diaphragm, is vibrated by a longitudinally movable member within a coil, the device being useful especially for telephonic uses and even more especially in devices used as aids for deaf people.

When the sound waves move the diaphragm

of the microphonic elements, such as 52, 53 or 70, the current is varied and, as above explained, this causes longitudinal movement of the piston armature, such as 17, with the result of conveying sound waves amplified as in Figures 7 and 9 or directly to the ear of a user as in Figures 5 3 and 8. The use of said longitudinally movable armature within a coil results in greatly increased movement of the vibratory element and consequently more effective action on the plate 36 of 10 Figure 7, or on the air between plate 9 and diaphragm 16 in Figure 3 and consequently in the latter case greatly increasing the action on the ear of the user, the sound waves passing through sound channel 9^b to the ear of the user. 15

What I claim is:

1. In an auricular telephone the combination 20 of a motor element; a vibratory element cooperating with the motor element; a case body; a perforated fixed plate above said vibratory element; a perforated ring cap to clamp said fixed plate to said case body; a rotatable front plate frictionally mounted on said fixed plate; and a sound tube on said rotatable plate.

2. In an auricular telephone the combination 25 of a motor element; a vibratory element cooperating with the motor element; a case body; a perforated fixed plate above said vibratory element; a grooved stud riveted to said fixed plate; a perforated ring cap to clamp said fixed plate 30 to said case body; a rotatable front plate mounted frictionally on said fixed plate; a sound tube on said rotatable front plate; and a detachable rubber tipped earwire frictionally mounted on said stud.

JOSEPH C. WHITE.
